UNITED STATES PATENT OFFICE.

CARL WILLIAM BILFINGER, OF WASHINGTON, NORTH CAROLINA.

WOOD-DISTILLING APPARATUS.

SPECIFICATION forming part of Letters Patent No. 658,888, dated October 2, 1900.

Application filed January 27, 1899. Serial No. 703,604. (No model.)

To all whom it may concern:

Be it known that I, CARL WILLIAM BILFINGER, of Washington, county of Beaufort, and State of North Carolina, have invented 5 certain new and useful Improvements in Wood-Distilling Apparatus, of which the following is a full, clear, and exact specification, reference being had to the accompanying drawings, wherein—

- 10 Figure 1 is a longitudinal sectional view on line 11, indicated in Fig. 2, and partly an elevation of my wood-distilling apparatus. Fig. 2 is a sectional view on line 22, indicated in Fig. 1. Figs. 3 and 4 are sectional views on line 33 and 44, respectively indicated in Fig. 2. Fig. 5 is a horizontal sectional view on line 55, indicated in Fig. 2. Figs. 6, 7, and 8 are detail views of the two separators and of the scrubber, respectively.
- 15 My invention relates to apparatus for the decomposition of wood for the purpose of obtaining therefrom all products of such distillation; and it consists of the hereinafter-described improvements in the construction of 20 wood-distilling apparatus, whereby all the products of the distillation—gas, fluids, and solids—are recovered absolutely separated 25 from each other and in condition most suitable for their utilization.
- 25 My improved apparatus is designed for carrying on a process of distilling wood which differs from the processes heretofore used, first, in the conduct of distillation, and, second, in the manner of separating the products 30 of such distillation.
- 35 In this apparatus the wood is distilled at a comparatively-low heat (not more than 800° of heat or thereabout at any stage of the distillation,) whereby excessive extraction and 40 the partial decomposition of tar and charcoal resulting therefrom are avoided. The tar is separated from the other products of distillation while yet in its primary state and discharged from the retorts before the distillation 45 of the wood is completed. The purpose of doing this is to prevent partial decomposition of the tar by evaporating its volatile ingredients and the mixing of the products of such decomposition with the other products 50 of distillation passing out at the top of the retort.

I have found it unprofitable to decompose tar in the process of producing illuminating-gas by distillation of wood. Not only is the gas obtained by decomposing tar of poorer 55 quality, but its purifying requires much more elaborate apparatus and materials not otherwise necessary for purifying of wood-gas. Moreover, by commingling the products of decomposition of tar with the products of distillation of wood also the other by-products, charcoal and turpentine, are detrimentally affected.

Decomposing of tar by distillation requires a considerably higher degree of heat than 65 the mere distillation of wood and produces, proportionately, a very much greater quantity of undesirable gaseous substances. These reduce the illuminating capacity of gas and increase the cost of its purification, and, 70 again, tar obtained by distillation of wood not exposed to a high degree of heat is purer and richer in desirable ingredients, rendering it capable of many uses and increasing also greatly its productive capacity for more 75 valuable final products. Still another advantage resulting from maintaining a low degree of heat in distilling wood and removing the tar from the retorts is the better quality of charcoal obtained thereby. It is well known 80 that charcoal if kept in glowing state develops great quantities of carbonic acid and in the same proportion loses its heating capacity. If the tar is decomposed in the retorts, the charcoal is necessarily exposed for a long 85 time to a high degree of heat, and consequently a great quantity of carbonic acid is developed from it, which passes out with the gas, which then requires more effort and expenditure to purify it, at the same time reducing the heating capacity of the charcoal.

The apparatus consists of an oven O, built, preferably, of masonry, with a furnace H in its base, a series of flues 2, J', J², and J³, arranged between the rows of retorts A and in 95 the inclosing walls, main flue H², chimney M, two or more rows of retorts A, conduits 5, main conduit 6, separators B and C, scrubber D, and their connections, outlet-pipes G, tar-conduit F, and of the various hereinafter-described auxiliary devices.

Retorts A are preferably cylindrical ves-

sels made of wrought-iron and covered on the outside with jackets 7, of fireproof clay or cement. Their tops are provided with charging-apertures 4, covered with removable lids 5 19 while the distillation is going on and with concaved bottoms, terminating in funnels a, connected by outlet-pipes G with tar-conduit F. Lids 19 are secured in place by braces 10 in a similar manner as the heads of boilers. Outlet-pipes G are closed with plugs or cocks 21 and are opened only from time to time to discharge the tar accumulating in the concaved bottoms of the retorts.

The system of flues is shown in Figs. 1 and 15 2. Flues H², R, R', R², and R³ connect furnace H directly with chimney M. Flues 2 are arranged parallel and crosswise around and between the retorts. They are divided in sections and provided with dampers 3 and 20 3', operated by rods 8 from the outside of the furnace. By correspondingly setting these dampers the current of combustive gases flowing from the furnace H to chimney M is directed through the sections of flues 2. The 25 combustive gases may be passed directly to the chimney or through flues 2 around and between the retorts, and thus the heat acting upon the retorts increased or reduced. The flow of the combustion-gases through the 30 oven is indicated by arrows in Figs. 2 and 4 of the drawings.

A series of air-flues I I' J J' J², &c., (shown in Figs. 1, 2, 3, 4, and 5,) convey atmospheric air into various parts of the oven, supporting 35 the combustion of the fuel and increasing the efficiency of the apparatus. These air-flues are so located that the air is heated while passing through them. Flue I is laid beneath the furnace in the ash-pit and terminates in 40 the bottom of main flue H². A branch I' of this flue passes through bridge-wall K, discharging fresh air into the furnace beyond the grate. The flow of the draft-air through 45 this flue is regulated by damper 9, located beneath the ash-pit door. A second air-flue J is laid parallel with and immediately above the arch of the furnace. This flue divides into branches J' J² J³, &c., opening into successive sections of flues 2. The inlet of flue J 50 is provided with a slide, and by increasing or reducing the area of the opening the draft of air through these flues J J' J², &c., is regulated. The flow of the air through the air-flues is indicated by arrows in Figs. 2 and 3 55 of the drawings.

On starting the fire in the furnace all branches of flues 2 are closed and the smoke and gases pass from the furnace through flues H², R, R', R², and R³ into the chimney M. Then 60 the dampers closing flues 2 are successively opened to let the combustion-gases pass around and between the retorts. Dampers 3 and 3' when turned to open flues 2 close at the same time flues R', R², and R³, thus 65 diverting the flow of combustion-gases to pass into flues 2. Then the supply of draft-air

through the oven is gradually increased by opening the slides until the heat is raised to approximately 800° Fahernheit. This highest heat is maintained only when the distilling 70 operation is nearly completed.

Conduits 5 convey the volatile products of wood distillation through the main conduit 6 into the separator B. This separator is a hermetically-closed vessel having an inclined 75 bottom, with a discharge-cock 11 set in its lower point and connected by pipe 13 with the condensing-separator C. This condensing-separator is also a hermetically-closed vessel, with an inlet at the terminal of pipe 13 and 80 an outlet at the pipe 15. A coiled pipe N, entering the separator C at n and leaving it at n', is connected to a pump, drawing a continuous stream of cold water through the separator. In place of water any other cooling 85 medium may be used.

Pipe or conduit 15 starts horizontally from the lowest point of the condensing-separator C and branches off vertically toward the scrubber D. Some distance from the separator is a downwardly-pointing tube 16, branching off of the conduit 15. Through this tube provided with stop-cock 17 the liquid products of condensation are conveyed from separator C to the refining apparatus. The incondensable gas passes through conduit 15 into scrubber D, wherein it is purified in the usual manner by eliminating therefrom carbonic acid and other ingredients affecting its illuminating quality. Scrubber D is connected by 90 conduit V with a reservoir. (Not shown in the drawings.)

The liquefied by-products accumulating in separator B are not recharged into the retorts or redistilled, as was done heretofore. The 105 heavy oils precipitated in separator B are more valuable when treated separately to recover from them their component elements or to convert them into other substances. They may be used for many purposes in the 110 state as recovered, whereas if they are partly decomposed by reheating similar disadvantages result, as described, with reference to tar.

The gaseous substances passing from separator B into the separator C are not reheated, 115 because the more volatile substances contained therein would be thereby decomposed or brought in a state in which their condensing could not be well accomplished with the simple means provided in the condensing-separator C. The main component of these more volatile substances is pure turpentine, which in a volatile state is capable of absorbing carbonic acid and other carbonaceous 120 gases produced by decomposition of tar or of such heavier oils as are precipitated in separator B. The quality of turpentine would be greatly diminished by such absorption. By distilling wood in the manner described I am able to obtain almost absolutely pure 125 turpentine and illuminating-gas of high efficiency requiring but little treatment to purify 130

the same (hydrate of lime or other similar substances being preferably used for that purpose) to render it almost absolutely pure.

I claim as my invention and desire to secure 5 by Letters Patent—

1. A wood-distilling apparatus comprising an oven a furnace, smoke and air flues arranged in the oven in sections as herein shown and described, means for diverting the flow 10 of combustion-gases through each section independently of the others; retorts set in the oven and having charging-apertures in their tops; removable lids upon the apertures and means for securing them thereon; funnel-shaped bottoms with outlets provided with 15 means for closing the same, for discharging the tar; and conduits for withdrawing the volatile products of the distillation from the retorts.
2. An oven for a wood-distilling apparatus, comprising a furnace, a chamber above the furnace, a smoke-flue from the furnace to the chimney alongside the chamber and separated therefrom by a partition-wall, a series 20 of horizontal walls dividing the chamber into sections, apertures in the partition-wall form-

ing an inlet and an outlet for each section of the chamber; dampers closing the apertures in the partition-wall, and means for dividing the adjoining smoke-flue into compartments 30 corresponding with the sections of the damper.

3. An oven for a wood-distilling apparatus, comprising a furnace, a chamber above the furnace, a smoke-flue from the furnace to the chimney alongside the chamber and separated therefrom by a partition-wall, a series 35 of horizontal walls dividing the chamber into sections; air-flues arranged in the horizontal walls and in the partition-wall and opening into the chamber; apertures in the outer wall 40 of the oven communicating with the air-flues and means for closing the same; apertures in the partition-wall forming an inlet and an outlet for each section of the chamber; dampers closing the apertures in the partition-wall, 45 and means for dividing the adjoining smoke-flue into compartments corresponding with the sections of the damper.

CARL WILLIAM BILFINGER.
